UNITED STATES PATENT OFFICE.

JOHN J. FRANK, OF PITTSFIELD, MASSACHUSETTS, ASSIGNOR TO GENERAL ELECTRIC COMPANY, A CORPORATION OF NEW YORK.

SYSTEM OF ELECTRICAL DISTRIBUTION.

1,112,283.

Specification of Letters Patent. Patented Sept. 29, 1914.

Application filed September 5, 1912. Serial No. 712,666.

To all whom it may concern:

Be it known that I, JOHN J. FRANK, a citizen of the United States, residing at Pittsfield, county of Berkshire, State of Massachusetts, have invented certain new and useful Improvements in Systems of Electrical Distribution, of which the following is a specification.

The present invention relates more especially to vapor electric apparatus such, for example, as alternating current mercury vapor rectifiers or lamps and is applicable to such devices whether the same be arranged for operation with single-phase current or with multi-phase current.

It is the object of my invention to provide for a rectifier or similar device a unitary structure comprising both supply reactances for obtaining a point of intermediate potential and a sustaining cathode reactance.

By this construction I am enabled to secure an apparatus of less weight, less cost, less bulk, and of higher efficiency because the iron core is utilized for both sets of coils and with less total energy loss. This core is so arranged with respect to the coils that it forms a closed magnetic circuit with respect to those coils which provide the point of intermediate potential and at the same time it operates as an open magnetic circuit for the coil in the cathode circuit.

The scope of my invention is more particularly set forth in the claims appended hereto while the invention itself will perhaps be better understood by reference to the following description taken in connection with the accompanying drawing which shows my invention embodied, by way of illustration, in a mercury arc rectifier system.

The rectifier consists as usual of an exhausted envelop 1 containing main anodes 2 and 3 and a coöperating cathode 4. It is also provided with a starting anode 5, the function of which is now well understood. The anodes are connected to alternating current supply conductors 6 and 7 across which are connected inductance coils 8 and 9. These coils are wound upon separate legs 50 of a magnetic core 10 and have two terminals connected to each other as indicated. The flux generated by these coils passes through the closed magnetic circuit afforded by the core. The cathode circuit includes a storage battery load 11 which is connected

in series by means of conductor 12 with an inductance coil 13 to the common connection for the alternating current inductance coils 8 and 9. The coil 13 is wound around the outside of the core 10, and the circuit of its flux is therefore completed partially through the air. In the drawing it is indicated as being placed transversely across cores 8 and 9 and superposed upon coils 8 and 9, but this is not essential. Inasmuch as the magnetic flux caused by coils 8 and 9 is pulsating and as the flux caused in the core by coil 13 is not in the same direction as the pulsating flux generated by coils 8 and 9, a single core may be used in this manner to advantage. The unidirectional flux of coil 13 opposes the flux generated by coils 8 and 9 in one half of the core and assists it to an equal extent in the other half, thus causing no increase in the total resultant flux. In this manner, the effect of a large core for coil 13 is secured without additional expense.

What I claim as new and desire to secure by Letters Patent of the United States, is:—

1. The combination of a winding, a vapor electric device having its anodes connected to terminals of said winding and its cathode to an intermediate point, an inductive coil in the cathode circuit, and a core forming a closed magnetic circuit with respect to said winding and an open magnetic circuit with respect to said coil.

2. The combination of a closed magnetic core, coils wound upon legs of said core and having a common connection, a vapor electric device having its anodes connected to the free terminals of said coils, and its cathode to the common connection and an inductive coil in the cathode circuit surrounding said core.

3. In a system of distribution, the combination of current supply leads, a rectifying device having anodes connected thereto, inductance coils connected across said leads and providing a point of intermediate potential, another inductance coil in series with the cathode and connected to said intermediate point, and a core common to all said coils providing a closed magnetic circuit for the coils in the anode circuit and an open magnetic circuit for the cathode coil.

4. An electrical system, comprising the combination of a core, coils wound on separate legs of said core, a series connection for

said coils, a device having unidirectional conductivity, connections between respective anodes of said device and terminals of said coils, a coil wound over the outside of said core as a whole and connections for said coil to a cathode of said device and to an intermediate point on said series connected coils.

5. An electrical system, comprising the combination of current supply leads, a magnetic core, inductance coils wound on separate legs of said core and connected across said leads and in series with each other, a device having a plurality of anodes connect-

ed respectively to terminals of said coils and a cathode connected to an intermediate point, and a coil in series with said cathode carrying unidirectional current and wound outside both the series connected coils and said core as a whole.

In witness whereof, I have hereunto set my hand this 3rd day of Sept., 1912.

JOHN J. FRANK.
